ALBERT J. OLLENDORF.

By Arthur E. Wallace Atty.

UNITED STATES PATENT OFFICE.

ERSKINE WILDER, OF HUBBARD WOODS, AND ALBERT J. OLLENDORF, OF OAK PARK, ILLINOIS.

DISPLAY BOX.

Application filed December 9, 1922. Serial No. 605,964.

To all whom it may concern:

Be it known that we, ERSKINE WILDER and ALBERT J. OLLENDORF, citizens of the United States, residing, respectively, at 5 Hubbard Woods, in the county of Cook and State of Illinois, and at Oak Park, in the county of Cook and State of Illinois, have invented a new and useful Display Box, of which the following is a specification.

The present invention has to do with goods containers and relates more particularly to containers for advertising display.

Among the objects of the invention are, 15 the supplying of a box construction whereby fiber may be employed for the production of display containers; the provision of a box construction of simplified structure and formed from interfitting blanks of fiber 20 or the like; the production of a unique structure for a box with reinforcements disposed with respect to the strain thereupon; and the provision of a novelty in blank formation whereby to produce in the finished container an outstanding reproduction of an object to be displayed in conjunction with the container.

These, and such other objects as may hereinafter appear, are obtained by the novel 30 construction, combination and arrangement of the several parts of our device, which is fully disclosed in the accompanying single sheet of drawing, made a part of this specification, and in which:

35 Fig. 1 is a perspective view of the completed display container;

Fig. 2 and Fig. 3 illustrate the two blanks employed in our box construction;

40 Fig. 4 is a vertical section of the container along the line 4—4 of Fig. 1 looking in the direction of the arrows;

Figs. 5 and 6 are fragmentary sectional details along the lines 5—5 and 6—6 of Fig. 4, and

45 Fig. 7 is a vertical section of the display container in closed position.

Like reference characters are used to designate similar parts in the several views of the drawing and in the description of the 50 device which follows.

In order to understand the invention, ref-

erence will first be had to Figs. 2 and 3, which illustrate the blanks from which our display container or box is produced.

In Fig. 2 is the blank A, which provides 55 the outer section of the bottom, designated 10, the rear wall or back side of the box designated 11, and the top or cover of the display cabinet, which for purposes of description is divided into three sections later 60 to be discussed. With the exception of two extensions projecting from the back wall 11, such extensions being designated 12, the blank A may be wholly rectangular although it is desirable to round the corners of 65 the top thereof. The point of folding intermediate the bottom section 10 and the back wall 11, and the back wall 11 and the top, are deeply scored, such scores being indicated by the dotted lines in the figures. 70 Between extensions 12 and the back wall 11 are similar deep scores.

The first of the three sections of the top is the rear portion 13 adjacent the back wall 11 and out of the material of which the 75 object or objects to be depicted (in this case a shoe sole) is or are cut, except for a short section or portion thereof which projects over into the second section of the top, designated 14, which is separated from 80 the rear portion or section 13 by scoring as indicated by the broken line in Fig. 2. Said scoring extends the full length of the material except across that portion of the object or objects which project from section 13 85 over upon section 14. The numeral 15 is used to designate the partly cut-out object to project above the folded box cover. The last and outermost section of the cover may be called a lip, and is separated from section 14 by a score also indicated by a broken line.

In Fig. 3, the second blank which includes 95 the remaining portions of our box structure is illustrated and designated by the letter B. Such blank B comprises a bottom portion 16 corresponding in configuration to that of section 10 of blank A, upon which latter section said section 16 is placed in the assembly of the box structure. The 100 front of the box comprises two narrow sections contiguous to section 16, and separated

therefrom and from one another by scores. The front side or portion of the box is designated 17 and is only slightly greater than one half the height of the box, while the 5 extension thereof, designated 18, is folded over against the inside of front 17 in the completed structure. Tacks such as are clearly illustrated in Fig. 5 are disposed at spaced intervals to hold section 18 in proper 10 relation to section 17, and elsewhere in the structure where required.

The blank B further comprises two wing portions separated from section 17 by scores, but cut entirely clear of sections 16 and 18 15 during the stamping out of the blank. The wings referred to are identical except that one is a right hand wing and the other is a left hand wing and each is of a length equivalent to the width of the finished box. 20 Said wing portions are rectangular in configuration and each comprises three sections. The largest of said sections is designated 19, and is of the same width as section 16, and is separated from the remaining 25 portions of the wing by a score which is an extension of that separating sections 16 and 17.

The next adjacent portion of each wing is designated 20 and forms the end of the 30 box. As already indicated, said sections are separated from section 19 by scoring which scoring indicates the line of the bottom of the box structure. Extensions 21 separated from end portions 20 by scores parallel to the 35 longitudinal outer edge of section 18 completes the blank structure with the exception of the short scores between section 17 and each of the wing sections which scoring connects the line cuts intermediate sections 16 and 18 and said wing portions.

As has been indicated, the first step in assembling the box is to fold section 18 over onto section 17 and tack or clamp the same into position. The second step is to 40 fold the wings upwardly with respect to the central section of blank B. Section 19 should then be folded to a 90° angle with respect to section 20. Blank B is then placed upon blank A with section 16 coinciding with section 10, and with section 17 forming one outermost extremity of the structure. Sections 19 are disposed within the box to rest upon section 16. The three bottom thicknesses 10, 16 and 19 are then 45 clamped or glued together. Sections 20 are thus made to project backwardly from section 17 to form the ends of the container. The extension 12 of the back wall 11 are folded inwardly and then tacked to the inside of the lower portions of sections 20. Extensions 21 are next folded inwardly 50 over the walls of sections 20 and of extensions 12, and the whole tacked together, which operation completes the production 55 of the box.

If the box is to be used in closed position, the top is folded along the scores intermediate sections 11 and 13, and 14 and the lip, so that said top section extends over the top of the container, and the open and upper portion of the front side of said container is closed by the lip bent downwardly at a 90° angle from said sections 13 and 14. 70

To display soles, a sole being the object particularly referred to in the specific construction here shown, the top is folded at 180° upon the score between sections 13 and 14, the section 13 then being an extension upwardly of the rear wall 11, and the section 15 being an extension of section 14 vertically downward. When section 14 is folded inwardly upon section 13, as indicated, the cut-out portion or tongue 15 becomes an extension from section 14, and projects upwardly above the fold intermediate said sections, as is clearly shown in Figs. 1 and 4. The lip or extension 15 is inserted intermediate the end wall 20 and the rear wall 11, the extension 21 engaging the extreme ends of lip 15 to hold it in vertical and parallel alinement with rear wall 11 and section 13. 80

The material which we have employed with considerable success is fiber, and we believe that this is the first successful embodiment of fiber material in a display container. 85

Of course other materials may be employed, but one of the objects of our invention is the production of a structure adapted and suitable for sheet fiber. It is manifest that many other articles very different from a shoe sole may be depicted by the cut-out portion 15, and our invention is not limited, therefore, either to a projecting portion shaped to represent a shoe sole, or to the specific structure here employed, for many modifications thereof may be made without departing from the spirit of the invention. Our invention, therefore, is fully 100 set out in the claim hereto appended. 105

We claim:

A carton for packing and displaying merchandise, comprising two blanks of sheet material and having the upper edges of its ends and its front of two thicknesses of material, each of said blanks being of substantially rectangular configuration and provided with two separated extension portions, said blanks cooperating one with another, when in assembled relation, to provide for said carton a bottom of three thicknesses of material, the body of the first of said blanks providing the back, top, and a lip at the front of said carton, the extensions on said blank forming means for uniting said first blank to said second blank, and the second of said blanks having extension portions and forming two layers of the bottom 115 of said carton, the reinforced ends, and the 120 125 130

reinforced front thereof, the extension portions of said blank overlapping the extension portions of said first blank for uniting said blanks one to another, said first blank being adapted to be folded longitudinally through the top section thereof to expose in outline an object advertising the

contents of the carton, the cover section when so folded being held upright by the overlapping portions of the extensions on 10 said second blank.

ERSKINE WILDER.
ALBERT J. OLLENDORF.
